UNITED STATES PATENT OFFICE

2,477,493

BUN SLICING DEVICE

Birger O. Olson, Chicago, Ill.

Application April 25, 1946, Serial No. 664,843

1 Claim. (Cl. 146—150)

1

This invention relates to new and useful improvements and structural refinements in bun slicing devices, and the principal object of the invention is to provide a device of the character herein described, such as may be conveniently and effectively employed for multiple slicing of buns, rolls, or the like, in restaurants, hamburger stands, and similar other establishments.

In conventional practice, it is customary to place an individual bun on the table and to slice the same in a horizontal plane while pressing down or otherwise holding its upper portion. Where it is necessary to slice a multitude of buns more or less at the same time, the tediousness of the individual slicing operation as above set forth, becomes clearly apparent. For this reason, it is frequently found that the operator will attempt to hold two or more buns with one hand while endeavoring to slice them with a knife in the other, this being a practice which not only produces inefficient results in cutting, but often injures the hands of the operator.

It is therefore, a further object of the invention to eliminate the disadvantages above set forth, by providing a device in which a plurality of buns may be sliced efficiently, safely, and conveniently, at one time.

Another object of the invention is to provide a device which is simple in construction and which cannot easily become damaged.

An additional object of the invention is to provide a device which may be readily kept clean.

A still further object of the invention is to provide a device which may be readily adjusted to accommodate different sizes of buns.

With the above more important objects in view, and such other objects as may become apparent as this specification proceeds, the invention consists essentially of the arrangement and construction of parts as illustrated in the accompanying drawings, in which—

Figure 1 is a top plan view of the invention.

Figure 2 is a side elevation thereof.

Figure 3 is a cross-sectional view, taken in the plane of the line 3—3 in Figure 1, and

Figure 4 is a cross-sectional view, taken in the plane of the line 4—4 in Figure 1.

Like characters of reference are used to designate like parts in the specification and throughout the several views.

Referring now to the accompanying drawings in detail, the invention consists of a substantially rectangular, horizontally disposed base 5, such as may be conveniently positioned on a table top.

2

A pair of end members 6 and a pair of side members 7 are secured to the marginal edge portion of the base 5 and constitute a frame defining a channel-like recess 8, adapted to receive a plurality of buns 9. It will be noted that the end members and the side members may be suitably connected together at the corners of the base by means of mortise and tenon joints, as illustrated in the accompanying drawings.

An end strap 10 is, in turn, secured to each of the end members 6, and a further pair of longitudinally extending straps 11 and 12 are positioned on the straps 10.

By virtue of the spacing action of the straps 10, the straps 11 and 12 will co-act with the side members 7 to provide a pair of transversely aligned slots 13, such as may be effectively employed to guide the movement of the slicing knife 14. The strap 11 is firmly secured in position, but the strap 12 may be adjusted to vary the relative spacing thereof with respect to the strap 11, as will be presently described.

The strap 12 is formed adjacent the ends thereof with suitable apertures 14, and a pair 25 of downwardly projecting pins 15 are pressed into these apertures, as will be clearly apparent from the accompanying drawings. Further apertures 16 are provided in an aligned relationship in each of the end members 6, these 30 last-mentioned apertures also penetrating strap 10, the base 5, and the mortise and tenon joint of the associated members 6 and 7.

It will be apparent that by inserting the projecting portion of the pins 15 in any longitudinally aligned pair of apertures 16, the relative spacing of the straps 11, 12 may be correspondingly varied.

When the invention is placed in use, the buns 9 are placed in the recess 8, as illustrated in the 40 accompanying Figure 1. Thereupon, by passing the knife 14 through the slots 13, the slicing of the buns may be efficiently and safely undertaken. It will be noted that by adjusting the position of the strap 12 with respect to the strap 11, the device may be readily adapted to accommodate various sizes (diameters) of buns.

It is believed that the use and advantages of the invention will be clearly understood from the foregoing disclosure and accordingly, further description thereof at this point is considered unnecessary.

What I claim as my invention is:

A bun slicing device comprising a substantially rectangular base member, a pair of side members carried by said base, tongues projecting from

the terminals of said side members, a pair of end members carried by said base, recesses at the terminals of said end members slidably engaging said tongues, said side members, end members and base member being formed with a plurality of aligned apertures, dowel pins frictionally engaging said aligned apertures for removal of said side members, said end members and said base member from each other, said side members and end members defining a bun receiving chamber, a pair of transverse straps secured to said end members and overlying the latter, a fixed longitudinal strap secured to said transverse straps and spaced parallel to one of said side members, a movable longitudinal strap adjacent the other of said side members and coplanar with said fixed longitudinal strap, a plurality of aligned openings provided in said movable longitudinal strap, and in said transverse straps, in alignment with the aforementioned apertures in said end members, and said base member, a longitudinal blade engaging recess

provided between said longitudinal straps and said side members, and connecting pins engageable in said aligned openings for selected adjustment of said movable longitudinal strap relative to said fixed longitudinal strap, said transverse straps limiting the longitudinal movement of a blade in said blade engaging recess.

BIRGER O. OLSON.
